Staten Island, N.Y. 10304

Filed Aug. 11, 1967, Ser. No. 8,236

Term of patent 14 years

(Cl. D83—1)

FIGURE 1 is a top perspective view of a surgical multi-procedure instrument table embodying my new design.

FIG. 2 is an end elevational view thereof, and

FIG. 3 is a rear elevational view thereof.

The characteristic features of my design reside in the specific arrangement of an overshell in combination with a conventional hospital table as best illustrated in FIGS. 1 and 2 on the drawing.

I claim:

The ornamental design for a surgical multi-procedure instrument table, substantially as shown and described.
